UNITED STATES PATENT OFFICE.

PETER SHARP, OF PERTH, SCOTLAND.

BOBBIN FOR SPINNING MACHINES.

Application filed December 21, 1926, Serial No. 156,143, and in Great Britain September 10, 1925.

This invention relates to means for mounting and applying drag to bobbins for spinning machines in which said bobbins are mounted upon positively driven spindles, 5 and the object is to provide extremely simple and efficient means for the automatic regulation of the thread tension so as to maintain said tension at the proper degree as the diameter of the bobbin increases during the 10 winding of the thread thereon.

The invention comprises an improved drag embodying a resilient member or members capable of being adjustably applied to the bobbin and the tension of which varies 15 according to the diameter of the bobbin, whereby the required drag on the bobbin as the winding proceeds is automatically obtained.

The invention is hereinafter fully described and pointed out in the appended claims with reference to the accompanying drawings in which:—

Fig. 1 is a sectional elevation with parts broken away and showing two bobbins, and 25 Fig. 2 is a sectional plan of Fig. 1 showing particularly the improved form of drag.

As shown in the drawings I provide the base a^1 of the bobbin a (which rests on the usual rising and falling bobbin bar or builder plate b) with a recess c formed by an enlargement of the bore of the bobbin through which the spindle d passes; and I fit this recess, which may be approximately about half an inch in depth, over an 30 upwardly boss e on the builder plate b , this boss embracing the spindle d as it passes into the bobbin.

The boss mentioned may be attached to, or formed in one with the builder plate or, as 40 shown, carried by a separate plate or member h directly carried by the builder plate by screws h^1 so long as it supports the bobbin in the manner stated. The provision of such a boss prevents the bobbin a being 45 pressed laterally against the spindle d and its speed being consequently accelerated due to the increased pressure as the winding proceeds and the speed gets greater, since it always keeps the bobbin properly centred. 50 In addition to the usual bottom friction of the bobbin a on the builder plate b there is a certain amount of friction between the boss e and the recess c in the base of the bobbin which acts as a brake to control the 55 rotation of the bobbin.

The efficiency of such bobbin mounting

may be further increased by recessing or increasing the interior bore of the bobbin upwards from the base or bobbin to a diameter slightly larger than that of the spindle; for example, $\frac{1}{16}$ inch increase as shown at i on the left of Figs. 1 and 2. Such increased diameter extends to within a short distance of the top of the bobbin, for instance to $1\frac{1}{4}$ inches therefrom, the remainder 60 of the bore at j being practically the same as that of the spindle d , that is to say, making a substantially close fit thereon. The distance of the enlarged bore i from the top of the bobbin may be varied according to 65 requirements. The bobbin thus cannot engage the spindle at the enlarged bore but is steadied and centred by the reduced bore at the top and by the boss e on the builder plate or other support which engages the recess e in the base and on which the bobbin 70 revolves.

The improved drag shown more particularly in Fig. 2 includes a resilient or flexible member or members which will cause the 80 braking effect to become automatically greater as the speed of the bobbin increases during the winding. The tension of said resilient member thus varies with the speed of the bobbin, and accommodates itself to the 85 degree of winding, so that the drag automatically applies the required amount of braking force at all times.

The improved form of drag differs from those hitherto known comprising an inextensible weighted member adapted to engage a groove a^2 in the base of the bobbin, such as a plain leather or fibre band commonly provided with an attached depending weight, in that it embodies a flexible and resilient member comprising, for instance a spring or elastic element f as of rubber followed by a length of leather or other inextensible material g and then another spring or elastic element f^1 . 90

One end of said drag is secured to one side of the builder plate b , for example being secured to a flange b^1 thereof by means of a rivet f^2 ; the inextensible member then passes about the groove a^2 in the bobbin base to 95 brake same and the opposite end f^1 is engaged on the other side of the builder plate, such as by entering one of a series of notches b^3 in a flange b^2 of said plate as usually practised. The end of the drag may be however provided with a hook f^3 which engages 105 under the edge of the builder plate as shown 110

in Fig. 1. The latter connection is detachable to vary the amount of initial tension required to provide for differences in the size of bobbin used by shifting the end of the 5 drag into different notches nearer to or farther from the axis of the bobbin, but under ordinary running, and particularly with the use of the boss *e* above described, the resiliency braking effect exerted by the drag is 10 sufficient to automatically control the speed by reason of the elasticity of said drag which is tensioned to a greater or less extent as the speed of the bobbin increases or decreases during the filling of same.

15 It will be apparent from the above description that the mounting of the bobbin *a* on the boss *e* which is centrally fixed allows the rotation of the bobbin to be easier than with known forms of mounting and prevents 20 tendency of the bobbin to rise during its rotation. The improved form of drag also exerts pressure only on one side of the bobbin *a* and on one side of the boss *e*, such pressure being taken up by the boss and tending to 25 provide for a uniform steady motion of the bobbin. Again with the drag of the present invention no shifting of the drag is necessary during the winding of the bobbin, the brak-

ing action being entirely automatic, and the pressure on the bobbin is very limited, wear 30 and tear on the bobbin being thus reduced to a minimum. The above constructions render it possible for a much finer and weaker thread or yarn to be spun on the same bobbin as at present, owing to the centralization produced by the boss *e* on which the bobbin rotates, and the resiliency of the drag which will permit it to give, due to possible temporary stoppage of the bobbin owing to slight lumps on the thread, and 40 then to immediately resume its normal condition.

What I claim as my invention and desire to secure by Letters Patent of the United States is:—

1. A drag for a spinning bobbin including an inextensible member and an elastic member in combination with said inextensible member.

2. A drag for a spinning bobbin including an inextensible member, and elastic members connected one to each end of said inextensible member.

In witness whereof I have signed this specification.

PETER SHARP.
